UNITED STATES PATENT OFFICE.

GEORGE POMEROY, OF SAN FRANCISCO, CALIFORNIA, ASSIGNOR TO PANAMA-PACIFIC INTERNATIONAL EXPOSITION COMPANY, OF SAN FRANCISCO, CALIFORNIA, A CORPORATION OF CALIFORNIA.

DESIGN FOR A BADGE.

43,557.

Specification for Design.

Patented Feb. 11, 1913.

Application filed November 19, 1912. Serial No. 732,374. Term of patent 3½ years.

To all whom it may concern:

Be it known that I, GEORGE POMEROY, a citizen of the United States, residing in the city and county of San Francisco and State of California, have invented a new, original, and ornamental Design for Badges, of which the following is a specification, reference being had to the accompanying drawing, forming part thereof.

The figure is a view of the obverse face of the badge.

I claim:

The ornamental design for a badge, as shown.

GEORGE POMEROY.

Witnesses:

CHAS. LEWIS,
GEO. C. SAMPSON.
